DESIGN FOR A DOMESTIC WATER HEATER

Jack Barofsky, Los Angeles, Calif.

Application March 17, 1942, Serial No. 106,217

Term of patent 14 years

To all whom it may concern:

Be it known that I, Jack Barofsky, a citizen of the United States, residing at Los Angeles, in the county of Los Angeles and State of California, have invented a new, original, and ornamental Design for a Domestic Water Heater, of which the following is a specification, reference being had to the accompanying drawing, forming part thereof.

The side opposite that shown in the drawing is the same as the side illustrated.

I claim:
The ornamental design for a domestic water heater, as shown and described.

JACK BAROFSKY.
